(57) **CLAIM**

I claim the ornamental design for a memory card component, as shown and described.

DESCRIPTION

FIG. 1 is a top plan view of my new design in accordance with the present invention;

FIG. 2 is a front view thereof;

FIG. 3 is a top perspective view thereof;

FIG. 4 is a bottom view thereof;

FIG. 5 is a side view thereof;

FIG. 6 is an opposite side view thereof; and,

FIG. 7 is a bottom perspective view thereof.

Broken lines and portions entirely contained within broken lines are not claimed.
